UNITED STATES PATENT OFFICE.

PETER E. POLLANO, OF PITTSBURGH, PENNSYLVANIA.

DESIGN FOR A LAMP.

Application filed September 22, 1924. Serial No. 10,861. Term of patent 14 years.

To all whom it may concern:

Be it known that I, PETER E. POLLANO, a citizen of the United States, residing at Pittsburgh, in the county of Allegheny, State of Pennsylvania, have invented a new, original, and ornamental Design for a Lamp, of which the following is a specification, reference being had to the accompanying drawing, forming a part thereof.

The figure is a perspective view of a lamp provided with a base embodying my design.

I claim:
The ornamental design for a lamp, as shown.

PETER E. POLLANO.
